UNITED STATES PATENT OFFICE.

FREDERIC MARTIN, JR., OF COLUMBUS, OHIO.

RUBBING-SURFACE FOR WASHBOARDS.

SPECIFICATION forming part of Letters Patent No. 726,082, dated April 21, 1903.

Application filed May 5, 1902. Serial No. 105,914. (No model.)

To all whom it may concern:

Be it known that I, FREDERIC MARTIN, Jr., a citizen of the United States, residing at Columbus, in the county of Franklin and State 5 of Ohio, have invented a certain new and useful Improvement in Rubbing-Surfaces for Washboards, of which the following is a specification.

My invention relates to the improvement of 10 rubbing-surfaces for washboards; and the objects of my invention are to provide a washboard rubbing-surface of improved construction and to so form my improved rubbing-surface as to present a desirable arrangement 15 of frictional rubbing projections which will greatly facilitate the cleansing of the material rubbed thereon. These objects I accomplish in the manner illustrated in the accompanying drawings, in which—

20 Figure 1 is a face view of a washboard having my improved rubbing-surface. Fig. 2 is a central longitudinal section of the same, and Fig. 3 is a detail view in perspective of a portion of said rubbing-surface.

25 Similar numerals refer to similar parts throughout the several views.

In carrying out my invention I employ a suitable washboard-frame, which may be of the usual form, (indicated at 1.) Mounted 30 in this frame between the side frame-pieces and between the upper and lower cross-pieces 2 is my improved rubbing-plate 3, of the form hereinafter described. This rubbing-plate, which is of zinc or other suitable material, 35 has formed throughout its length a plurality of parallel and adjoining rows of oblong projections 4, the upper end of one of these projections extending outward from the base of the next higher projection, thereby forming 40 the successively-arranged shoulders 5. In the arrangement of the rows of projections 4 the top or shoulder portions 5 of the projections in one row are brought opposite the centers of the lengths of the corresponding 45 projections of the rows on either side thereof, thus bringing the shoulders or heads of the projections of the alternate rows in trans-

verse alinement. As a result of the successive projections and the alternate arrangement of the same above-described it is obvious that the space between the upper portions of two equal-height projections 4 and above the shoulder portion 5 of the intermediate projection will form a water-receiving recess and that these recesses are thereby brought into diagonal alinement and communication.

It will be observed by referring to the drawings that the herein-described rubbing or frictional projections are angular in longitudinal section, the upper and front faces of each projection being flat, thus distinguishing the same from rounded projections, various forms of which have been employed heretofore.

It is obvious that I may form the rubbing-plate with the straight rear side, which is indicated in Fig. 2, or by the usual process of indenting the body of the sheet or plate. (Indicated in Fig. 3.)

From the construction which I have herein shown and described it will readily be seen that a simple and effective form of rubbing-surface is produced, which through the formation and relative arrangement of its frictional projections and water-receptacles will greatly facilitate the thorough cleansing of the material which is brought into frictional contact therewith.

Having now fully described my invention, what I claim, and desire to secure by Letters Patent, is—

A washboard rubbing-plate comprising a plate-body having formed therein parallel longitudinal rows of separated friction projections, the projections of one of said longitudinal rows breaking joint with the projections of the adjoining rows and each of said projections being formed with flat outer side and upper end surfaces which meet approximately at right angles, substantially as specified. 90

FREDERIC MARTIN, JR.
